United States Patent Office

Des. 202,233
Patented Sept. 7, 1965

202,233

LINE CASTING MACHINE

William B. Abbott, Pleasantville, and Louis Rossetto,
Kings Point, N.Y., and Robert H. Hose, Summit, N.J.,
assignors to Eltra Corporation, a corporation of New
York

Filed Apr. 15, 1963, Ser. No. 74,452

Term of patent 14 years

(Cl. D64—11)

Fig:1.

Des. 202,233

PAGE 2

Fig:2.

Fig. 3.

FIG. 1 is a front and right side perspective view of a line casting machine showing our new design;

FIG. 2 is a front and left side perspective view; and

FIG. 3 is a rear and right side perspective view thereof. Parts of the keyboard have been omitted from FIGS. 1 and 2 for convenience of illustration.

The essential features of our design reside in the parts shown in solid lines.

We claim:

The ornamental design for a line casting machine, as shown and described.
